THOMAS K. KEITH, OF BOSTON, MASSACHUSETTS, ASSIGNOR, BY DIRECT AND MESNE ASSIGNMENTS, TO CHARLES F. BROWN, TRUSTEE, OF READING, MASSACHUSETTS.

BOTTLE-LABELING MACHINE.

SPECIFICATION forming part of Letters Patent No. 762,826, dated June 14, 1904.

Application filed April 13, 1903. Serial No. 152,409. (No model.)

To all whom it may concern:

Be it known that I, THOMAS K. KEITH, of Boston, in the county of Suffolk and State of Massachusetts, have invented certain new and useful Improvements in Bottle-Labeling Machines, of which the following is a specification.

This invention has for its object to enable a series of bottles contained in a case having separate cells or pockets for the bottles to be removed successively from the casing, labeled, and returned to the case, the whole operation being performed automatically.

The invention consists in the improvements hereinafter described relating to a machine having bottle-grasping jaws which are reciprocated vertically, means for supporting a bottle-holding case below said jaws and for feeding said case step by step in the directions required to bring each bottle-holding cell successively into position under the jaws, so that the jaws may withdraw each bottle from its cell and subsequently return it thereto, and means for applying labels to the bottles while they are held raised above the case or holder, all as hereinafter described and claimed.

Of the accompanying drawings, forming a part of this specification, Figure 1 represents a front elevation of a bottle-labeling machine embodying my invention. Figs. 2 and 3 represent opposite end elevations of the machine. Fig. 4 represents a plan view of portions of the machine, other portions being removed and certain parts shown in section. Fig. 5 represents a section on line 5-5 of Fig. 1 looking toward the left. Figs. 6 to 13, inclusive, represent detail views of parts hereinafter referred to. Fig. 14 represents a perspective view of one of the feed-rolls provided with printing characters.

The same reference characters indicate the same parts in all the figures.

In the drawings, 12 represents an arm or standard forming a part of the supporting-frame of the machine, said arm overhanging the bed or table 13, which supports the compound slide or carrier, hereinafter described, on which the bottle-holding case 15 is held.

17 represents a reciprocating rod or plunger vertically movable in guides 18 18 50 on the arm 12. To the lower end portion of the plunger 17 are pivoted at 19 a series of jaws 20, of which there may be any suitable number, three being the number preferred. Said jaws are adapted to grasp the neck of a 55 bottle 21 in the case 15 and to lift the bottle from the case when the plunger 17 rises.

22 represents a driving-shaft journaled in the frame of the machine below the bed or table 13. Said shaft imparts motion to the 60 plunger 17 and to the various operating parts hereinafter described. The means here shown for imparting motion from the driving-shaft to the plunger comprise a cam 23, affixed to the driving-shaft, a lever 24, pivoted at 25 to 65 the supporting-frame, a lever 26, pivoted at 27 to the supporting-frame, a link 28, connecting the levers 24 and 26, and a bell-crank lever 29, pivoted at 30, one arm of said lever being forked and engaged with a collar 31 on 70 the plunger 17, while the other arm bears against the upper end of the lever 26. A spring 32, engaged with one arm of the bell-crank lever 29, normally depresses said arm and the plunger 17, said spring acting through 75 the described connections to hold the lever 24 yieldingly against the cam 23.

33 represents a ring adapted to encircle a bottle 21. Said ring is affixed to one arm of a bell-crank lever 34, Fig. 3, which is pivoted 80 at 35 and is oscillated by means presently described to give the ring upward and downward movements, the ring being alternately raised above the bottle under the jaws and depressed to encircle said bottle. The bell-crank 85 lever 34 is operated to give the ring the movement above stated by means of a cam 36, Fig. 15, on the driving-shaft 22, a lever 37, pivoted at 38 and having a trundle-roll 39 bearing against the perimeter of said cam, a link 90 40, connecting the lever 37 with one arm of the fulcrum-lever 34, and a spring 41, which normally pulls the ring-supporting arm of the lever 34 downwardly and holds the trundle-roll 39 in yielding contact with the cam 95 36. The ring 33 descends upon the bottle be-

fore the jaws descend to grasp it, the ring acting to open or spread the jaws as they descend upon the bottle, so that their hooked inner sides will pass over the enlarged mouth of the bottle, the ring subsequently releasing the lower ends of the jaws and permitting them to close upon the neck of the bottle below its enlarged upper end. The jaws are provided with inclines 42 at their lower ends, Figs. 6, 10 7, and 8, these inclines striking the outer edge of the ring as the jaws descend and causing the opening or spreading of the jaws. The ring subsequently rises with the jaws and bottle and encircles the lower portion of the bottle, steadyng the same during the subsequent operation of applying the label.

The bottle-holding case 15 is provided with the usual bottle - holding cells or compartments arranged in rows, means being provided for holding the case in a series of different positions under the jaws, so that the jaws will successively engage, raise, and return each bottle. The case 15 rests upon a secondary slide 43, which is movable back and forth on a primary slide 44, the latter having guides 45 embracing the edges of the secondary slide 43. Mechanism is provided for moving the secondary slide in the directions indicated by the arrow *x* in Fig. 1 and for 20 moving the primary slide, and with it the secondary slide, in the directions indicated by the arrow *y*, Fig. 3. Step-by-step motions in two directions are therefore imparted to the slide and the bottle-holding case thereon, 25 these motions being such that the bottles are brought successively under the jaws.

The mechanism for moving the primary slide comprises a cam 46, Fig. 3, on the driving-shaft, a lever 47, pivoted at 48 and having a trundle-roll 49 bearing against the perimeter of the cam 46, a spring 50, holding said trundle-roll yieldingly against the cam, a dog 51, pivoted to the swinging end of the lever 47, a ratchet-wheel 52, journaled upon a fixed bearing 53, its teeth being engaged by the dog 51, a rod or pitman 54, pivoted at 55 to the ratchet-wheel 52, a rock-shaft 56, journaled in fixed bearings on the supporting-frame and having an arm 57, to which one 30 end of the link 54 is pivoted, and another arm 58, which is connected by a link 59 with the primary slide 44. The oscillations of the lever 47, caused by the spring 50 and cam 46, impart a step-by-step rotation to the ratchet-wheel 52 through the dog 51, said wheel imparting corresponding movements through the described intermediate connections to the primary slide, the latter being therefore moved back and forth in the directions indicated by 35 the arrow *y*.

The means employed for moving the secondary slide comprise a cam 60, Fig. 5, on the driving-shaft; a lever 61, pivoted at its lower end to the supporting-frame and having 40 a trundle-roll 62, which is held by a spring 63

in contact with the perimeter of the cam 60; a vertical rock-shaft 64, journaled in bearings on the supporting-frame; a ratchet-wheel 65, affixed to said shaft and engaged by a pawl 66, carried by a reciprocating arm or carrier 67, 45 engaged with the swinging end of the lever 61, the back-and-forth movements of said lever being imparted, through the arm or carrier 67, to the dog 66 and causing the latter to impart a step-by-step rotation through the ratchet 65 50 to the rock-shaft 64; a cam 68, affixed to the rock-shaft 64; a horizontal rock-shaft 69, having an arm 70 normally held in the path of the cam 68; an arm 71, Fig. 1, affixed to the rock-shaft 69 and projecting upwardly through 55 a slot in the bed or table 13; a dog 72, carried by the swinging end of the arm 71 and adapted to engage teeth or projections 73 on the under side of the secondary slide 43, and a spring 74, which acts to retract the arm 71 and dog 50 72 and hold the arm 70 within the path of the cam 68. The described mechanism imparts an oscillatory movement to the arm 71 and a back-and-forth movement to the dog 72, the latter being pivoted to the arm 71 and pressed 60 upwardly by a spring against the under side of the secondary slide 43. Each movement of the dog 72 in the direction of the arrow *x* in Fig. 1 moves the secondary slide one step in the same direction. This movement occurs 65 after the primary slide has moved step by step a distance equal to the width of the bottle-case 15, so that after each of the bottles of a transverse row in the bottle-case has been 70 acted on by the jaws the case is moved endwise a distance equal to the space between the center line of each row of bottles and the center line of the next row to bring another row into 75 position to be acted on by the jaws. It will be seen that the step-by-step movements 80 imparted to the primary slide are in opposite directions, said slide being moved step by step, first in one direction and then backwardly, whereas the movement imparted to the secondary slide is in one direction only. After 85 the last bottle in the case has been acted on the case is removed, and the secondary slide is returned by hand to its starting position and is ready to receive another case.

Means are employed for applying a label to 90 each bottle while it is held in raised position, said means in this embodiment of my invention being organized as follows: 75 represents a coiled strip of printed labels mounted upon a stud or spindle 76, which projects upwardly 95 from a bracket or holder 77, affixed to the supporting-frame. One side of the strip is gummed, and the strip is conducted beside a moistening-pad 78 and fed forward under the jaws 20 when the latter are raised, so that the 100 forward end of the strip stands beside and projects across one side of the bottle held by the jaws. The strip 75 is fed forward step by step by means of feed-rolls 79 79, mounted 105 on suitable fixed bearings on the frame of 110

the machine. The shafts of said feed-rolls are connected by intermeshing gears 80. The rolls are rotated step by step by means of an arm 81, pivoted at 82 to an oscillating lever 83, which is moved back and forth, as hereinafter described, the said arm 81 having ratchet-teeth which engage a ratchet-wheel 85, affixed to the shaft of one of the feed-rolls 79. The oscillatory movements of the lever 83 cause the arm 81 to alternately engage and rotate the ratchet 85 and to move backwardly without rotating said ratchet, its teeth slipping on the teeth of the ratchet during its backward movement. The forward movement thus imparted to the ratchet 85 is imparted by the latter to the feed-roll with which it is connected and by the gears 80 to the other feed-roll. The lever 83 is oscillated by means of a cam 86, Fig. 2, on the driving-shaft, a lever 87, pivoted at 88 and connected at its lower end by a link or rod 89 with the swinging end of a lever 90, having a trundle-roll 91, bearing against the perimeter of the cam 86, the upper end of the lever 87 being connected by a link 92 with the swinging end of the lever 83.

The label-strip is pressed against the bottle by means of two jaws 93 93, which are pivoted at 94 to each other and to one arm of a bell-crank lever 95. Said lever is pivoted at 96 to the supporting-frame and is oscillated by means hereinafter described, so as to move the jaws 93 toward and from the bottle held in a raised position by the jaws. The label-strip may be 35 perforated or partially cut through at intervals between the sections of printed matter, so that the pressure of the jaws against the strip will have the effect of detaching a section of the strip constituting a complete label, 40 said section being pressed by the jaws against the bottle. I prefer, however, to provide means for cutting off each section from the strip. To this end I have shown a fixed cutter 97 and a movable cutter 98, said cutters 45 coöperating after the manner of shear-blades and being arranged to sever the label-strip just after the advancing end of the strip has been pressed against the bottle by one of the jaws 93. Said jaws are preferably arranged 50 so that one of them engages the label and presses it against the bottle, as shown in Fig. 10, before the other reaches the extreme of its forward movement, so that the label is cut off before its rear end is pressed against the 55 bottle by the second jaw. The lever 95 is oscillated to move the jaws 93 93 toward and from the bottle by means of a cam 99, Fig. 2, on the driving-shaft, a lever 100, having a trundle-roll which is pressed by a spring 60 against said cam, and suitable connections 101 102 122 between the lever 100 and the lever 95. The jaws 93 cross each other at the point where they are pivoted, and each has a rearwardly-extending arm 103, which is beveled at 65 its rear end, as shown at 104, Figs. 11 and 12.

105 represents a vertical pin which is yieldingly supported by a spring 106 and is arranged to occupy the recess formed by the beveled ends 104 when the jaws are projected against the bottle, Fig. 9. When the jaws 70 are retracted, the pin 105 forces the arms 103 apart, and thus causes the jaws 93 to swing outwardly away from the detached label, so that there is no tendency on the part of the jaws to drag the label from the bottle. The 75 arms 103 are recessed at their inner sides to form an opening 107, Fig. 11, which receives the pin 105 when the jaws are retracted. The under sides of the arms 103 are beveled, as shown at 108, Fig. 13, these beveled portions 80 bearing upon the pin 105 when the jaws are again moved forward, depressing the pin, so that the arms 103 slide over it during the forward movement of the jaws.

The operation of the machine is as follows: 85 The primary and secondary slides are first adjusted so that one corner of the bottle-case 15 is under the jaws, which are now assumed to be elevated. The ring 33 descends over the bottle below it, the jaws descending after the 90 ring. The downward movement of the ring is arrested briefly before the ring reaches the extreme of its downward movement, thus allowing the ring to act on the inclines 42 of the jaws and open the latter before they reach the 95 top of the bottle-neck. The ring is then moved farther downward, releasing the jaws and allowing them to grasp the bottle-neck. The jaws now rise and lift the bottle from the case, the ring moving upwardly with the jaws 100 and remaining in engagement with the lower portion of the bottle, so that the bottle is steadied and prevented from tipping or swinging in the jaws during the operation of detaching the label. While the bottle is being 105 raised, the label-strip is fed forward, so that when the bottle reaches its highest point enough of the strip for one label has been advanced beside the bottle. The jaws 93 then advance, one of the jaws pressing the outer 110 end of the label-strip against the bottle. The cutter then severs a label from the strip and the second jaw then presses the rear end of the label against the bottle. The pressing-jaws then recede and the bottle-holding jaws 115 descend and deposit the labeled bottle in the compartment of the case from which it was removed. The jaws and ring then rise above the bottle, and the case is given a sufficient movement to bring the next bottle in position 120 under the jaws, when the above-described operation is repeated.

I do not limit myself to the details of mechanism herein described, as said details may be variously modified without departing from 125 the spirit of my invention.

The feed-roll 79, which bears on the outer side of the label-strip, may be formed as an impression-roll provided with printing characters, as shown in Fig. 14, adapted to print 130

the labels while they are being fed forward, the other feed-roll acting as a bed-roll. Suitable means may be employed for inking the impression-roll.

5 The jaws 20 have arms 200 projecting above their pivots 19. The lower plunger-guide 18 is so formed and arranged that when the jaws 20 are elevated the arms 200 are in contact with said bearing and are pressed outwardly 10 thereby, so that the jaws are correspondingly pressed inwardly and caused to firmly grasp the bottle during the operation of applying the label.

15 The movable cutter 98 is oscillated by a cam 110, affixed to one of the feed-rolls, Fig. 4, said cam forcing the cutter in one direction, and a spring 112, which holds the cutter yielding against the cam.

I claim—

20 1. A machine of the character specified, comprising a plunger, bottle-grasping jaws carried thereby, means for reciprocating the plunger and jaws, means for presenting a bottle to said jaws, and means for applying a 25 label to the bottle held by the jaws.

2. A machine of the character specified, comprising a plunger, bottle-grasping jaws carried thereby, means for reciprocating the plunger and jaws, means for presenting a number 30 of bottles successively to said jaws when the latter are at one end of their movement, and means for applying labels to the bottles held by the jaws.

3. A machine of the character specified, comprising a plunger, bottle-grasping jaws carried thereby, means for reciprocating the plunger and jaws, a bottle case or holder, means for moving said bottle-case in the directions required to present the bottles successively to said jaws, and means for applying labels to the bottles held by the jaws.

4. A machine of the character specified, comprising a plunger, bottle-grasping jaws carried thereby, means for reciprocating the 45 plunger and jaws, means for presenting a bottle to the jaws, a bottle-encircling and jaw-opening ring located below the jaws, means for raising and depressing said ring, and means for applying a label to the bottle held by said 50 jaws and ring.

5. A machine of the character specified, comprising a plunger, bottle-grasping jaws

carried thereby, means for reciprocating the plunger and jaws, means for presenting a bottle to said jaws, feed-rolls arranged to feed a 55 label-strip to the bottle held by the jaws, and means for pressing a part of said strip against the bottle.

6. A machine of the character specified, comprising a plunger, bottle-grasping jaws 60 carried thereby, means for reciprocating the plunger and jaws, means for presenting a bottle to said jaws, feed-rolls arranged to feed a label-strip to the bottle held by the jaws, means for rendering one side of the strip adhesive, 65 and means for pressing a part of the strip against the bottle.

7. A machine of the character specified, comprising a plunger, bottle-grasping jaws carried thereby, means for reciprocating the 70 plunger and jaws, means for presenting a bottle to said jaws, feed-rolls arranged to feed a label-strip to the bottle held by the jaws, means for pressing the outer end portion of the strip against a bottle held by the jaws, and means 75 for severing a label from the strip.

8. A machine of the character specified, comprising a plunger, bottle-grasping jaws carried thereby, means for reciprocating the plunger and jaws, a primary slide located below the jaws, a secondary slide supported by the primary slide and adapted to support a bottle case or holder, means for moving the primary slide back and forth step by step, means for moving the secondary slide on the primary 85 slide in one direction step by step, said primary and secondary slides presenting a number of bottles successively to the jaws, and means for applying labels to the bottles held by the jaws.

9. A machine of the character specified, comprising a plunger, bottle-grasping jaws carried thereby, means for reciprocating the plunger and jaws, means for presenting bottles to said jaws, and feed-rolls arranged to 95 feed a label-strip to a bottle held by the jaws, one of said rolls having printing characters adapted to print the strip.

In testimony whereof I have affixed my signature in presence of two witnesses.

THOMAS K. KEITH.
